Primary Examiner — Ian Simmons*Assistant Examiner* — Mark Cavanna(74) *Attorney, Agent, or Firm* — Sterne, Kessler,
Goldstein & Fox P.L.L.C.(57) **CLAIM**

The ornamental design for a gas burner, as shown and described.

DESCRIPTION

FIG. 1 is a top perspective view of a gas burner showing our new design;

FIG. 2 is a front view thereof;

FIG. 3 is a top view thereof;

FIG. 4 is a bottom view thereof; and,

FIG. 5 is a bottom perspective view thereof.

The broken lines in the figures show portions of the gas burner that form no part of the claimed design.
